UNITED STATES PATENT OFFICE.

HENRY F. WINKELMANN, OF NEBRASKA CITY, NEBRASKA.

ROOF CONSTRUCTION.

1,073,551.

Specification of Letters Patent.

Patented Sept. 16, 1913.

Application filed August 5, 1910. Serial No. 575,675.

To all whom it may concern:

Be it known that I, HENRY F. WINKELMANN, a citizen of the United States, residing at Nebraska City, in the county of Otoe and State of Nebraska, have invented new and useful Improvements in Roof Construction of which the following is a specification.

The invention relates to roofing and more particularly to the class of roof constructions or coverings.

The primary object of the invention is the provision of a roofing or covering in which the material thereof is rendered impervious to water, thus preventing leakage of the same, and at the same time excluding heat and cold or moisture from a building.

Another object of the invention is the provision of a roofing or covering which will be light in weight, yet possessing the requisite strength and durability, and also that will resist fire, hail, water, moisture, heat, cold, sounds, and lightning, thus increasing the life of the roofing.

A further object of the invention is the provision of a roofing or covering construction which possesses innumerable advantages and superiority in roofing, heretofore well known in the art, and being simple in construction, and one that is inexpensive in the production thereof.

The invention resides generally in the formation of a composite roofing or covering combined with reinforcing means, thus giving rigidity and strength thereto, and at the same time compensating for expansion and contraction thereof by reason of climatic changes.

With these and other objects in view, the invention consists in the construction, combination and arrangement of parts, as will be hereinafter more fully described, illustrated in the accompanying drawings and pointed out in the claim hereunto appended.

In the drawings: Figure 1 is a fragmentary top plan view of a roofing constructed in accordance with the invention. Fig. 2 is a similar view, the same being partly broken away. Fig. 3 is a transverse sectional view on the line 3--3 of Fig. 1. Fig. 4 is a fragmentary perspective view of the metallic lath used in the roofing construction. Fig. 5 is a detail perspective view of one of the tie or bonding rods.

Similar reference characters indicate corresponding parts throughout the several views of the drawings.

Referring to the drawings by numerals, 5 designates the vertical walls of a building which is provided with sheeting 6 of any suitable material, and upon which the composite roofing is placed, as will be herein-after more fully described. Superimposed upon the upper face of the sheeting 6 are a plurality of plies of felt 7, the same being suitably impregnated with tar-pitch, and these plies entirely cover the said sheeting so that their edges will contact with the inner faces of the vertical walls 5 rising a slight distance above the sheeting at the top of the building. The outermost ply of felt 7 is coated with any suitable water-proof paint. Extending across the outermost ply of felt 7 at intervals throughout the area of the top of the building are tie or bonding rods 8, the ends of the same being passed through the vertical wall 5 and to which are suitably secured disks or anchoring plates 9, the latter contacting with the outer faces of opposite walls of the said building.

Resting upon the tie or bonding rods 8 and spaced from the outermost ply 7, is a metallic lath, the same being constructed from a single piece of sheet metal cut to provide spaced parallel webs 10 united to each other by means of diagonally disposed connecting strips 11, the webs 10 being inclined relative to the upper ply of felt 7, thereby effecting a waved formation to the said lath throughout the entire area thereof. The connecting strips 11 uniting the webs 10 are spaced at intervals from each other, so as to provide suitable gaps between the said strips 11 for a purpose, as will be herein-after more fully described. Upon this metallic lath is arranged a cementitious block 12, the same being preferably composed of two parts of sand and one part of cement, thoroughly commingled or mixed, the composition being applied to the metallic lath when in a soft state, so that the substance will percolate through the spaces between the strips 11 and webs 10 of the lath, whereby the latter will materially reinforce the substance when hardened. It will be obvious that by reason of the disposition of the inclined webs 10 and also the strips 11, this substance when in a soft condition will be

prevented from spreading or running while being poured or otherwise distributed over the metallic lath.

In the upper face of the block 12 are formed spaced longitudinally and vertically disposed channels or grooves 13, the vertically disposed grooves intersecting said longitudinal grooves and into which is poured pitch or asphaltum 14, when in a molten condition, the pitch or asphaltum entirely filling the channels or grooves which extend only through substantially one-half of the thickness of the block 12. By reason of this construction, the block 12 is prevented from breaking caused by expansion and contraction due to exposure to climatic changes or variable weather conditions.

The metallic lath interposed between the tie rods 8 and the cementitious block by reason of its inclined webs 10 relative to the plies of felt serves to bond and set the substance of the said block, so as to prevent the running of the cement when applied, and also this cementitious substance will be caused, by slight pressure thereon, to enter the space of interstices between the webs and the connecting strips 11, thus assisting in the proper setting of the cement constituting the block. Engaging the webs 10 of the said metallic lath and the tie or bonding rods 8 are staples 15, the same being driven into the plies of felt and the sheeting of the roof, thus securely fastening the said lath against any displacement. It will be noted that by reason of this metallic lath being superim-

posed upon the tie rods, it will be elevated from the uppermost ply or felt so as to be embedded within the cementitious block, thereby materially reinforcing the same. On the upper or outer face of the cementitious block is applied a cement slushing which fills all pores of the said block, throughout the entire surface thereof, thus rendering the same impervious to water.

From the foregoing, it is thought that the construction of the invention will be clear, and therefore a more extended explanation has been omitted.

What is claimed is:

In combination, oppositely arranged walls, a layer of pliable material extending longitudinally between said walls, a plurality of spaced-apart tie rods extending across and above said pliable layer and engaging said walls, a woven metal net-work member extending across and resting upon said tie rods, a plastic layer surmounting said woven metal member throughout its area and completely embedding the same and said tie rods, and bearing upon said pliable layer, and staples engaging said woven-metal members, straddling said tie-rods and driven into said pliable layer of material.

In testimony whereof I affix my signature in presence of two witnesses.

HENRY F. WINKELMANN.
